UNITED STATES PATENT OFFICE.

FRANKLIN H. BULLIS, OF BROOKLYN, NEW YORK.

WAVE TURNER.

Application filed May 1, 1922. Serial No. 557,650.

To all whom it may concern:

Be it known that I, FRANKLIN H. BULLIS, a citizen of the United States, and residing at Brooklyn, in the county of Kings and 5 State of New York, have invented certain new and useful Improvements in Wave Turners, of which the following is a specification such as will enable those skilled in the art to which it appertains to make and 10 use the same.

This invention relates to wave turners and particularly to apparatus of this class adapted for use in connection with steam-boats, ships, vessels and the like, and the 15 object of the invention is to provide an apparatus of the class described which is adapted to be mounted in connection with a ship, boat or the like in such manner as to be moved into operative position whenever 20 desired to catch the waves produced by the progress of a ship, boat or the like through a water-way and to turn said waves backwardly toward the ship or to break the formation thereof; a further object being to 25 provide means for moving said apparatus into operative and inoperative positions and for holding the same in such positions; and with these and other objects in view the invention consists in an apparatus of the class 30 and for the purpose specified which is simple in construction, efficient in use and which is constructed as hereinafter described and claimed.

The invention is fully disclosed in the 35 following specification, of which the accompanying drawing forms a part, in which the separate parts of my improvement are designated by suitable reference characters in each of the views, and in which:—

40 Fig. 1 is a diagrammatic plan view of a ship, boat or the like showing four of my improved wave turners mounted in connection therewith;

Fig. 2 a partial section on the line 2—2 45 of Fig. 1 on an enlarged scale and illustrating the method of using one of my improved apparatus;

Fig. 3 a view looking in the direction of the arrow 3 of Fig. 2; and,

50 Fig. 4 a sectional detail view on the line 4—4 of Fig. 3 and on an enlarged scale.

In Fig. 1 of the drawing, I have diagrammatically indicated at 5 a steamship, boat, vessel or the like and have indicated four 55 of my improved wave turning apparatus 6

positioned thereon, two of said apparatus being located at the front end portion of the ship and on the opposite sides thereof to break and turn the waves generated at the sides of the ship in the progress thereof, 60 and the other two of said apparatus being located adjacent to the rear portion of the ship and on the opposite sides thereof.

It is the common practice on ships of various kinds and classes to provide a guard 65 rail 7 which projects beyond the hull of the vessel at a predetermined distance above the water line and, in practice, my improved wave turning apparatus is mounted in connection with said guard rail, and in Figs. 70 2, 3 and 4 of the drawing, I have shown one of my improved wave turning apparatus 6 on an enlarged scale and in detail.

My improved wave turning apparatus 6, as shown in the accompanying drawing, 75 comprises an oblong rectangular plate member 8 pivotally mounted in connection with and suspended from the guard rail 7 as shown at 9, three of these pivots being preferably employed, one at each end of the 80 plate 8 and one approximately centrally thereof, and the inner face of the plate 8 is preferably curved upwardly and inwardly as shown at 10 in Fig. 2 of the drawing; and this plate forms the wave turning 85 member or element of the apparatus, and may be moved into operative and inoperative positions by a suitable operating mechanism.

The operating mechanism for the plate 8 90 comprises a shaft 11 mounted in suitable bearings 12 suspended from the guard rail 7, said shaft being driven by a hand wheel, crank or the like on the shaft 13 extending upwardly through the guard rail with a 95 beveled gear 14 which meshes with a similar gear 15 on the shaft 11. A pawl and ratchet construction 16 is also employed on the hand wheel, crank or the like on the shaft 13 for holding the same against movement in one 100 direction, and it will be noted, on a consideration of Fig. 3 of the drawing, that forwardly directed brace rods 17 are employed for reinforcing the plate 8 in the event of said plate striking logs or other foreign matter in the water.

Pivotaly mounted in connection with the inner face of the plate 8 adjacent to the ends thereof are two arc-shaped rack members 18 adapted to cooperate with pinions 19 mount- 110

ed on the shaft 11 between the separate parts of the bearings 12 and rollers 20 are employed for holding the racks 18 in engagement with the pinions 19, said rollers being 5 mounted in the bearings 12 above the pinions 19.

The operation of my improved wave turning apparatus will be readily understood from the foregoing description when taken 10 in connection with the accompanying drawing and the following statement. It will be understood that normally the wave turning plate 8 will be held in the position indicated in dotted lines in Fig. 2 of the 15 drawing, or in an inoperative position while the ship is traveling at sea or in open water-way, but in entering a harbor or in traveling through a river or other comparatively narrow water-way where the waves 20 generated or produced by the progress of a ship through such water-way have caused considerable damage to breakwaters as well as to ships, vessels or the like anchored to docks along the waterfront, the wave turning 25 apparatus is then lowered into operative position as shown in full lines in Figs. 2 and 3 of the drawing by operating the hand wheels, cranks or the like on the shaft 13 of the separate apparatus to rotate the 30 shaft 11 and the gears 19 thereon, and to move said plates into operative positions by the rack members 19.

By reason of the upwardly and inwardly curved inner faces of the plates 8 of the 35 apparatus, the waves generated or produced by the progress of a ship through a water-way, such as above set out, will be caused to turn inwardly toward the ship as indicated at *x* in Fig. 2 of the drawing, in other 40 words, the plates 8 of the separate apparatus employed will operate to break up and destroy the waves produced by the ship in its progress through a water-way.

It will be noted that the plates 8 are so 45 mounted as to be directed forwardly and backwardly so as to not retard the progress of the ship when in use, and while I have shown certain details of construction for carrying my invention into effect, it will be 50 apparent that I am not necessarily limited to these details, nor am I limited to any specific location or mounting of the apparatus in connection with a ship, boat or the like, and various changes in and modifications of 55 the construction herein shown and described may be made within the scope of the appended claims without departing from the spirit of my invention or sacrificing its advantages.

60 Having fully described my invention, what I claim as new and desire to secure by Letters Patent, is:—

1. A wave turning apparatus of the class 65 described comprising a wave turning element, means for movably mounting said ele-

ment in connection with a ship or the like, and into operative and inoperative positions, said wave turning element being curved concavely upwardly and inwardly on the inner face thereof to turn waves produced by said 70 ship inwardly in the direction of the ship.

2. A wave turning apparatus of the class described, adapted to be mounted in connection with a ship or the like and located at a predetermined distance from the hull 75 thereof and comprising a pivoted wave turning element, devices pivoted to the end portions of said element and by means of which the same may be moved into predetermined positions, a shaft mounted in connection 80 with the ship, and means on said shaft in connection with which said devices cooperate whereby the rotation of said shaft will operate said devices to move said element into predetermined positions. 85

3. A wave turning apparatus of the class described, adapted to be mounted in connection with a ship or the like and located at a predetermined distance from the hull 90 thereof and comprising a pivoted wave turning element, devices pivoted to the end portions of said element and by means of which the same may be moved into predetermined positions, a shaft mounted in connection with the ship, and means on said shaft in connection 95 with which said devices cooperate whereby the rotation of said shaft will operate said devices to move said element into predetermined positions, and means for rotating said shaft. 100

4. A wave turning apparatus of the class described, adapted to be mounted in connection with a ship or the like and located at a predetermined distance from the hull 105 thereof and comprising a pivoted wave turning element, devices pivoted to the end portions of said element and by means of which the same may be moved into predetermined positions, a shaft mounted in connection with the ship, means on said shaft in connection 110 with which said devices cooperate whereby the rotation of said shaft will operate said devices to move said element into predetermined positions, and means for rotating said shaft comprising a crank geared 115 in connection with said shaft. 120

5. A wave turning apparatus of the class described, adapted to be mounted in connection with a ship or the like and located at a predetermined distance from the hull 125 thereof and comprising a pivoted wave turning element, devices pivoted to the end portions of said element and by means of which the same may be moved into predetermined positions, a shaft mounted in connection with the ship, means on said shaft in connection with which said devices cooperate whereby the rotation of said shaft will operate said devices to move said element into predetermined positions, means for rotating said shaft com- 130

prising a crank geared in connection with said shaft, and means for reinforcing said element.

6. A wave turning apparatus of the class described, adapted to be mounted in connection with a ship or the like and located at a predetermined distance from the hull thereof and comprising a pivoted wave turning element, devices pivoted to the end portions 10 of said element and by means of which the same may be moved into predetermined positions, a shaft mounted in connection with the ship, means on said shaft in connection with which said devices cooperate whereby the rotation of said shaft will operate said devices to move said element into predetermined positions, and means for rotating said shaft 15 comprising a crank geared in connection

with said shaft, and the inner face of said element being curved inwardly and upwardly, toward the hull of the ship. 20

7. A wave turning apparatus of the class described comprising a wave turning element pivotally mounted in connection with and suspended from a stationary support, 25 operating devices pivotally mounted to said element, one face of said element being curved concavely upwardly and inwardly, and means for operating said devices for moving said elements into different positions. 30

In testimony that I claim the foregoing as my invention I have signed my name this 27th day of April, 1922.

FRANKLIN H. BULLIS.
